Atty.

UNITED STATES PATENT OFFICE.

KARL VIKTOR RUDIN, OF STOCKHOLM, SWEDEN.

NOTE-PAD.

1,259,779.

Specification of Letters Patent. Patented Mar. 19, 1918.

Application filed June 18, 1917. Serial No. 175,478.

To all whom it may concern:

Be it known that I, KARL VIKTOR RUDIN, correspondent, subject of the King of Sweden, residing at Karduansmakaregatan 5 12, Stockholm, Sweden, have invented certain new and useful Improvement in Note-Pads, of which the following is a specification.

The present invention relates to note-pads 10 having a plurality of piles of leaves of paper, fabric or other suitable material attached side by side to the same base plate and is chiefly characterized by the leaves of each pile being fastened together at the two 15 edges extending perpendicularly to the boundary-lines between the piles.

The advantage of this arrangement is chiefly that the upper surfaces of the piles offer a smooth plane and firm writing surface 20 and at the same time the notes can be easily overlooked and each note may be readily deleted.

The invention is illustrated on the accompanying drawing in which Figure 1 shows 25 a plan view of the note-pad and Fig. 2 a section of the same on the line A—B in Fig. 1. Fig. 3 shows a modification.

a designates the base which may consist 30 of paste-board or other suitable material. b designates the different leaf-piles which are attached to the mounting plate side by side so that the boundary-lines between them are parallel and their upper surfaces practically form one continuous writing surface. 35 The leaves of each pile are fastened together at two opposite edges c and d.

To obtain a practicable pad it is required 40 not only that the upper leaves together and separately form a smooth plane and firm writing surface but also that they are capable of being removed quickly and readily and independent of each other.

The above may be accomplished in any practical manner, but I preferably fasten the leaves of each pile together at the two 45 edges perpendicular to the parallel boundary-lines, as mentioned, in any suitable manner. By this arrangement it is attained that the separate leaves are kept smooth and plane thus forming a firm writing surface 50 and further that they may be readily removed.

In the pad shown in the drawing the leaves are fastened together by means of strips e 55 of paper or other suitable material. By cutting one corner of the leaves a certain part of one fastening edge has been left free of the fastening material, as shown at f in Fig. 1.

Evidently, two pads of the kind shown in 60 Fig. 1 may be bound together in the manner shown in Fig. 3 so as to form a book which can be folded up with the writing surfaces turned inward. By this arrangement the writing surface is increased and the notes 65 may be better protected and preserved. Further, the pad will obtain an increased stiffness.

Having now described my invention, what I claim is:

Note-pad consisting of two sets of piles 70 of note-leaves the leaves of each pile being fastened together at the two edges extending perpendicularly to the boundary lines between the piles and the two sets being 75 mounted so as to form a book with the writing surfaces of the two sets facing each other.

In testimony whereof I affix my signature in presence of two witnesses.

KARL VIKTOR RUDIN.

Witnesses:

JACOB BAGGS,
FRITZ E. HALLIN.
